United States Patent Office

Des. 186,043
Patented Sept. 1, 1959

186,043

CARAFE

Ernest L. Lilja, La Grange Park, Ill., assignor to Club Aluminum Products Company, Chicago, Ill., a corporation of Illinois

Application June 7, 1957, Serial No. 46,520

Term of patent 14 years

(Cl. D44—26)

Fig. 1 is a perspective view of a carafe, showing my new design;

Fig. 2 is an elevational view thereof; and

Fig. 3 is a top plan view thereof.

The handle and connecting band shown by dotted lines in Fig. 1 are for purposes of illustration only.

I claim:

The ornamental design for a carafe, substantially as shown and described.
